BAG FOR CLOTHESPINS AND GARMENT HANGERS

Magdalen Dalloz, Jacksonville, Fla.

Application December 16, 1941, Serial No. 423,250

3 Claims. (Cl. 150—1.8)

This invention relates to an improved bag for holding garment hangers and clothespins, it being one object of the invention to provide a bag which is of such construction that garment hangers and clothespins may be stored in pockets of the bag, where they will be shielded from dust and other dirt and thus prevented from becoming soiled when not in use.

Another object of the invention is to provide a bag wherein a bracing bar for the open upper end of the hanger-receiving pockets is mounted in a sheath extending across the pocket, the bar being inserted through an opening at one end of the sheath and the open end of the sheath being so formed that accidental displacement of the bar will be prevented.

Another object of the invention is to provide a bag of this character wherein the open ends of the pockets are normally closed and hangers and clothespins retained in the pockets against accidental loss and also prevented from being soiled.

Another object of the invention is to provide a bag of this character formed of fabric so cut that the bag is of simple construction and consisting of blanks so cut and assembled that marginal edges of certain of the elements or blanks form decorations for the bag.

Another object of the invention is to provide a bag which is strong and durable, of light weight, and easy to carry.

In the accompanying drawing:

Fig. 1 is a view showing the bag in front elevation with portions in section.

Fig. 2 is a sectional view taken vertically through the bag on the line 2—2 of Fig. 1.

Fig. 3 is a transverse sectional view on the line 3—3 of Fig. 1.

Fig. 4 is a fragmentary sectional view on the line 4—4 of Fig. 1.

This improved bag is intended to hold garment hangers, clothespins, as well as buttons, buckles, or the like; which are removed from dresses which are cleaned or laundered and hung from a clothesline. The bag is formed from denim or other suitable fabric and has a rear wall 1 and a front wall 2, in front of which is disposed a front panel 3, the walls 1 and 2 cooperating with each other to form a pocket 4 to receive clothes hangers and the front wall 2 and the forward panel cooperating with each other to form a front pocket 5. These pockets are open along their upper ends, as shown in Fig. 2, and by reference to this figure, it will be seen that the forward pocket is of less depth than the rear pocket and has its upper end terminating an appre-

ciable distance below the upper end of the rear pocket. Side edges of the blanks of fabric from which the walls and the panel are formed are sewed together by stitching 6, as are also their lower edges, and it should be noted that these edge portions of the blanks are first sewed to each other and the bag then turned to disposed seams formed by the stitching inwardly of the bag and provide the bag with neat appearing edges and rounded lower corners. The upper portion of the rear wall 1 extends upwardly from the upper edge of the front wall 2 and forms a flap 7 for shielding and closing the upper end of the rear pocket 4. The blanks for the walls and panel are so cut from the fabric that they have selvages along their upper ends and, since the selvage edges of the material are of a color contrasting with the color of the remainder of the fabric, bordering stripes 8, 9 and 10 are provided along their exposed edges to serve as decorations for the bag.

A strip 11 extends across the upper end of the front panel and is sewed along its upper and lower edges to this panel by stitching 12. The upper edge portion of the strip is turned under and sewed to the panel substantially even with the lower edge of the decorating strips 10 and the lower edge of this strip is a selvage edge to provide a smooth lower edge for the strip and also provide the strip with a decorating stripe 13 which cooperates with the stripe 10 to produce the effect of a strip having stripes 10 and 13 of a distinctive color along its upper and lower edges. This imparts a very attractive appearance to the bag. A strip 14 of elastic or elastic fabric extends through the transverse pocket formed by the strip 11 and, while stretched, has its ends sewed into seams formed by the stitching 6 so that as it contracts it will impart gathers to the upper edge portion of the panel and cause the forward pocket 5 to have a constricted open upper end which is normally held closed by contact of the upper end of the panel with the outer surface of the wall 2. When, however, clothespins are to be removed from the pocket 5, a hand may be easily thrust downwardly into the pocket and one or more clothespins withdrawn for use.

Representations of clothespins are provided upon the outer surface of the panel or wall 3, as shown at 15, by thread sewed through the fabric, and serve as decorations as well as serving to indicate that clothespins are to be stored in the pocket 5. In like manner, a representa-

tion of a clothes hanger is stitched into the flap 7, as shown at 16, to serve as a decoration and indicate that clothes hangers are to be stored in the pocket 4. A small sheet of fabric is sewed against the outer face of the panel to provide a patch pocket 17 into which buttons, buckles, and the like, removed from dresses or other garments, may be placed when hanging the garments from a clothesline. This pocket is preferably located centrally of the panel 13 between the representations of clothes pins 15 and has a colored selvage along its upper edge forming a decorating stripe 17' for the pocket.

A transverse pocket 18 is formed across the lower portion of the flap 7 by a strip of fabric 19 which has its upper and lower edge portions turned inwardly and secured by stitching 20. It should be noted that the strip 19 is so located that its lower edge portion is overlapped by the upper edge portion of the wall 2 and that one end of the strip is left unsecured to provide an open end for the pocket 18. Through this open end of the traverse pocket is inserted a stiff bar 21 which is preferably formed of wood but may be formed of other suitable material. The length of the bar is such that it extends the full length of the pocket 18 and opposite side faces of the bar are flat, as shown in Fig. 2, so that the bar will fit snugly within the pocket and be prevented from turning therein. The strap 22 by which the bag is carried is also formed from a strip of fabric and this strip is folded to provide a strap of double thickness. The strap is of appreciable width, its width being such that its end portions may fit snugly into ends of the pocket where it is secured to inturned side edge portions of the flap 7 by stitching 23. The end portions of the strap extend into the open end of the transverse pocket and the inturned edge portion of the flap to which it is secured forms a tongue under which the outer end of the bar 21 is disposed when the bar is fitted into the pocket and this tongue will serve to prevent the bar from accidentally slipping longitudinally out of the pocket. When the strap 22 is hung upon a hook or grasped to carry the bag, it extends in substantially a vertical plane with its lower ends directed inwardly into the transverse pocket and the pocket and the bar therein will be supported in substantially a horizontal plane and project forwardly over the upper end of the pocket 1 with the flap depending from the pocket. In this position, the upper end of the pocket 1 will be kept closed and shielded by the forwardly extending pocket and the depending flap, and dust and other dirt will be prevented from entering the pocket and settling upon garment hangers stored in the pocket. The bar 21 holds the upper portion of the bag stretched transversely and prevents it from collapsing. Therefore, the upper portion of the bag will be braced transversely and the open upper end of the pocket 1 pre-

vented from gaping open. At the same time, hangers may be easily removed from the bag or thrust therein.

Having thus described the invention, what is

5 claimed is:

1. A bag for holding garment hangers and clothespins comprising a body defining a hanger-receiving pocket having a rear wall and a front wall, the rear wall being extended upwardly 10 above the upper edge of the front wall to provide a flap foldable forwardly and downwardly into closing relation to the open top of the pocket, a strip extending across the inner surface of the flap and overlapped by the upper edge portion 15 of the front wall, said strip being secured along its upper and lower edges and across one end of the flap, the other end of the strip being free to provide an open end for a transverse pocket defined by the strip and the flap, a strap for 20 carrying the bag having its ends extending between the flap and ends of said strip and secured to the flap, the end of the strap extending into the open end of the transverse pocket and the portion of the flap to which it is secured forming a tongue, and a stiff bar removably fitted into the transverse pocket through the open end thereof and overlapped at one end by said tongue to prevent accidental displacement of the bar.

2. A bag of the character described comprising a body having front and rear walls and defining a pocket open at its top, the rear wall extending upwardly above the front wall to provide a flap foldable forwardly and downwardly into closing relation to the open top of the pocket, a strip 30 extending across the inner surface of said flap and stitched across one end and along its upper and lower edges to the flap to provide a transverse pocket open at one end, a strap for carrying the bag having its ends extending into ends of the transverse pocket and sewed to the flap, the end portion of the strap extending into the open end of the transverse pocket being extended to form a tongue, and a stiff bar removably fitted into the transverse pocket and having its outer end overlapped by the tongue to prevent accidental displacement of the bar.

3. A bag of the character described comprising a body having front and rear walls and defining a pocket open at its top, one wall being provided with a closure flap for the open end of the pocket, a strip secured across one end and along upper and lower edges to the inner surface of said flap and forming a transverse pocket extending across the flap and open at one end and having its lower portion overlapped by the other wall of the body, a stiffener removably fitted within the transverse pocket through the open end thereof, and a strap for carrying the bag having ends extending into ends of the transverse pocket and secured to the flap.

MAGDALEN DALLOZ.
